UNITED STATES PATENT OFFICE.

WILLIAM THOMAS BLACKWELL, OF WESTFIELD, NEW JERSEY, ASSIGNOR, BY MESNE ASSIGNMENTS, TO WESTINGHOUSE ELECTRIC & MANUFACTURING COMPANY, A CORPORATION OF PENNSYLVANIA.

LIGHTING FIXTURE.

Application filed January 18, 1922. Serial No. 530,200.

To all whom it may concern:

Be it known that I, WILLIAM THOMAS BLACKWELL, a citizen of the United States, and a resident of Westfield, in the county of 5 Union and State of New Jersey, have invented a new and useful Improvement in Lighting Fixtures, of which the following is a specification.

This invention relates to lighting fixtures 10 and more particularly to ornamental fixtures employed for indoor lighting.

An object of the invention is to provide the globe of a lighting unit with a simple and economically constructed cap for an 15 aperture in the globe.

Another object is to provide a cap which will add to the scheme of simplicity desirable in globes of this character.

A further object is to provide a cover 20 which may be quickly removed and replaced without the manipulation of mechanical elements.

Although the improved cover as herein contemplated may have general application 25 as a closure for apertures disposed in various parts of a globe or vessel, the present embodiment is an improvement of my co-pending application No. 522,746 filed Dec. 16, 1921, lighting fixture and assigned to 30 the Westinghouse Lamp Company, in which an aperture is disposed in the lower end thereof for the replacement of electric lamp bulbs.

Heretofore, covers for apertures for the 35 globes of lighting fixtures have included special fastening means such as screws, spring clips, etc. These mechanical elements are undesirable for the reason that they cast unsightly shadows, collect dust 40 and necessitate considerable manual manipulation to secure them to and remove them from the globe. Furthermore, when a light transmitting material such as glass is used considerable care must be exercised to prevent breakage.

It is well known that lighting fixtures 45 which are employed for indoor lighting should efficiently distribute the useful light and should also be constituted so as to appeal to the esthetic sense. In addition the fixture should be designed to harmonize with the appointments of the room in which it is employed and it will therefore be evident that the simplicity of my improved

cover is an important factor in the construction of a lighting unit. 55

It will readily be appreciated that additional advantages are attained by the present invention which provides a substantially non-breakable cover of such construction 60 that it may not only be quickly and conveniently secured to, or removed from, the globe but one which may possess the property of any desired degree of transparency. 65

The invention will be more fully understood by a reference to the following description and the accompanying drawings in which,

Fig. 1 is an elevation of a globe partly 70 in section showing my improved cap;

Fig. 2 is a fragmentary view of a globe showing another method of attaching the cap;

Fig. 3 is a fragmentary view of a globe 75 showing a cap of a modified construction; and

Fig. 4 is a bottom view of the globe as shown in Fig. 1 but on a reduced scale.

The invention provides a cover of a resilient character which may be readily distorted from its original configuration by the application of suitable force. It also possesses sufficient elasticity to resume its original configuration upon the removal of such force. By employing a cover having the 85 aforementioned property of elasticity, the said cover may have its normal diameter or area sufficiently greater than that of the aperture to effectively close the same when applied thereto and it may be temporarily 90 distorted to such configuration as to permit its entrance through the aperture. For instance, if the cover is of a circular shape it may be flexed or bent to an oval or elliptical shape and while thus flexed it may be 95 passed through the aperture of the globe, whereupon it may be permitted to readjust itself to its original configuration and become seated over the aperture to close the same. 100

To remove the cover from the globe, the cover is tilted until it takes a position with an edge thereof extending through the aperture, whereupon it may then be forcibly drawn therethrough, the necessary distortion of the cover being produced by its contact with the edges of the globe. 105

Any suitable flexible material may be em-

ployed for the cover, for example, celluloid or bakelite. The material may be translucent or opaque, or if an entirely opaque cover is desired, a cap of spun or stamped metal 5 may be employed.

When practicing the invention, a globe 5 of any suitable shape may be employed. The one illustrated, is provided with an aperture 6 at its lower end for the replacement 10 of an electric incandescent bulb 7 which is indicated in dotted lines. After a bulb has been inserted, the aperture 6 is closed by a cover or cap 8. The cap is sufficiently greater in diameter than the aperture 15 6 to provide a flange 9. This flange on the cover supports the latter when in its position as a closure for the globe and also prevents dust or other foreign substances from entering the globe.

20 The flange 9 of the cap (Fig. 1) is offset with respect to the body of the cap so that when the cap is in position to close the aperture the outer surface of the cap is flush with the outer surface of the globe. In Fig. 2 25 the flange 9 is omitted and the cap is provided with an annular depression 10 in which the edges of the globe surrounding the aperture engage when the cap is associated with the globe. In Fig. 3 a simple form of 30 cover is shown, which comprises a segment of a sphere. This type is desirable where a cap is required to carry out simplicity in design.

To apply the cover 8 to the aperture, the 35 cover is slightly deformed into an ellipse having its minor axis as indicated by the dotted line 11, of a lesser dimension than the diameter of the aperture 6. The cover is then inserted into the globe, the major axis 40 of the cover being maintained at an angle to the axial line of the globe. After the cap has passed through the aperture 6, it is permitted to resume its original shape, after 45 which it may readily seat itself to provide a cover as shown.

The simplicity of this cap makes it an important and desirable improvement in lighting fixtures, as the globe to which the cap is applied may be of simple construction without beading or complicated flanges such as 50 are usually employed with caps having mechanical attaching elements.

What is claimed is:

1. A lighting unit comprising a light 55 transmitting globe having an aperture in the light transmitting portion thereof and a

flexible cover having a larger diameter than said aperture, said cover being so constructed that it may be distorted when confined and readjusted when released, whereby 60 said cover may be inserted through said aperture to provide a cover therefor.

2. A lighting unit comprising a light transmitting globe having an aperture therein, a flexible cover having a larger diameter 65 than said aperture adapted to be temporarily deformed for entrance through said aperture and subsequently readjusted to its original shape and an annular flange offset with respect to the body of said cover, whereby 70 said body provides a flush surface with the outer surface of the globe when said cover is in position as a closure for said globe.

3. A cap for an aperture in a vessel, said 75 cap being composed of a substantially non-breakable flexible material adapted to be inserted into said vessel and supported on the interior surface of said vessel adjacent said aperture.

4. A lighting unit comprising a light- 80 transmitting globe having an opening in one portion thereof for the replacement of lamps, a deformable cover for said opening engaging the inner surface of said globe, and offset means in said cover for providing an 85 engagement of one portion of the outer surface thereof with the inner surface of said globe, another portion of the outer surface of said cover providing a continuation of said globe conforming to the contour of the outer 90 surface thereof.

5. A lighting unit comprising a light-transmitting globe having an opening in the bulbous portion thereof and a light-transmitting deformable closure for said opening, 95 said closure constituting an inwardly-retained element of said globe having an outwardly-disposed surface conforming to the contour of the outer surface of said globe.

6. A lighting unit comprising a light-transmitting globe having an opening in the normally lower bulbous portion thereof and a deformable closure for said opening, said closure constituting an inwardly-retained element of said globe having an outwardly-disposed surface conforming to the contour 100 of the outer surface of said globe.

In testimony whereof, I have hereunto subscribed my name this 12th day of January, 105 1922.

WILLIAM THOMAS BLACKWELL.
